UNITED STATES PATENT OFFICE.

HARRY F. CAVANAUGH, THEODORE S. HALL, AND ALBERT L. OLIVER, OF OAKLAND, CALIFORNIA, ASSIGNORS TO WONDER PORTABLE DISH WASHER COMPANY, OF EMERYVILLE, CALIFORNIA, A CORPORATION OF CALIFORNIA.

DESIGN FOR A DISHWASHING-MACHINE CASING.

Application filed October 4, 1922. Serial No. 3,876. Term of patent 3½ years.

To all whom it may concern:

Be it known that we, HARRY F. CAVANAUGH, THEODORE S. HALL, and ALBERT L. OLIVER, citizens of the United States, residing at the city of Oakland, county of Alameda, State of California, have invented a new, original, and ornamental Design for Dishwashing-Machine Casing, of which the following is a specification, reference being had to the accompanying drawing, forming part thereof.

Fig. 1 is a front view of the machine casing.

Fig. 2 is a side elevation of the same.
We claim:

The ornamental design for a dishwashing machine casing, as shown.

HARRY F. CAVANAUGH.
THEODORE S. HALL.
ALBERT L. OLIVER.
